Primary Examiner — Kevin K Rudzinski

(74) *Attorney, Agent, or Firm* — Ferguson Case Orr Paterson LLP

(57) **CLAIM**

The ornamental design for a kinematic shirt back, as shown and described.

DESCRIPTION

FIG. 1 is a rear isometric view of a kinematic shirt back in accordance with a first embodiment of the new design; FIG. 2 is a rear isometric view of a kinematic shirt back in accordance with a second embodiment of the new design; FIG. 3 is a rear isometric view of a kinematic shirt back in accordance with a third embodiment of the new design; and, FIG. 4 is a rear isometric view of a kinematic shirt back in accordance with a fourth embodiment of the new design. The broken lines shown in FIGS. 1-4 are directed to environment and are for illustrative purposes only; the broken lines form no part of the claimed design.

1 Claim, 4 Drawing Sheets
